GOLF CLUB OR SIMILAR ARTICLE

Robert P. Branch, 3950 Lake Shore Drive, Chicago, Ill.

Filed Apr. 15, 1959, Ser. No. 55,525

Term of patent 14 years

(Cl. D34—5)

Figure 1 is an elevational view of a golf club, showing my new design;

Fig. 2 is an enlarged side elevational view of the golf club design shown in Fig. 1;

Fig. 3 is a top plan view of Fig. 2; and

Fig. 4 is a left-hand elevational view of Fig. 2.

The broken line portions shown fragmentarily are for convenience of illustration.

The dominant features of the design are represented in full lines in the drawing and disclose an elongated, bulky, substantially cylindrically-shaped body having the opposite ends thereof of a substantially uniform semi-spherical configuration; the underside of said body, when in silhouette, being slightly convex; said body having an elongated centrally disposed rectilinear narrow facet formed in one of the side surfaces thereof; the oppo-

site ends of said facet being uniformly rounded and spaced from the end limits of said body and being substantially concentrically disposed with the corresponding ends of said body when viewed in elevation, as in Fig. 2.

I claim:

The ornamental design for a golf club or similar article, substantially as shown and described.
